(57) **CLAIM**

The ornamental design for a window blind headrail, as shown and described.

DESCRIPTION

FIG. 1 is an end view of the design;

FIG. 2 is a bottom view of the design;

FIG. 3 is a right side view of the design;

FIG. 4 is a top view of the design;

FIG. 5 is an upper right perspective view of the design; and, FIG. 6 is an upper left perspective view of the design.

The window blind headrail has been shown broken away in order to indicate that a specific length of window blind headrail forms no part of the claimed design. The broken line defining the breakaway also forms no part of the claimed design.
